ABSTRACT

An arrangement for protecting, at low loads, the furnace walls of a once-through steam generator system, having a recirculation loop, by increasing the mass flow of the working fluid flowing through the furnace wall tubes. A bypass for incoming feedwater is provided around the economizer allowing a lower temperature fluid to be delivered to and mixed with the fluid from the recirculation loop lowering the temperature of the fluid mixture. This results in a decrease in the specific volume of the mixed fluids; and since the recirculating pumps in the recirculation loop supply almost the same volumetric flow under all loads to the furnace wall tubes, the lower specific volume of the mixed fluid delivered to the pumps will yield a greater mass fluid flow to the furnace walls. The increased mass flow in turn results in improved heat transfer characteristics within the furnace walls thus reducing the likelihood of furnace wall damage due to overheating.

ECONOMIZER BYPASS FOR INCREASED FURNACE WALL PROTECTION

BACKGROUND AND SUMMARY OF THE INVENTION

This invention relates to once-through steam generator systems with recirculation through the furnace wall tubes, and more particularly to protection of the furnace wall tubes by increasing the mass flow therethrough.

In the start-up and low load operation of a once-through steam generator, it is necessary that fluid flow be established through the furnace wall tubes in order to protect the tubes from damage due to the heat generated by fuel firing. One present method of establishing this flow is recirculating a portion of the working fluid through the furnace wall tubes, in the manner shown and described in U.S. Pat. No. 3,135,252 to W. W. Schroedter. Protection according to this method is not entirely adequate for the desired furnace wall protection. It is, therefore, the purpose of our invention to provide improved furnace wall protection with minimum change to the existing arrangement.

During start-up and low load operation the fluid passed through the furnace walls of a once-through steam generator with recirculation consists of a mixture of heated feedwater from the economizer and recirculated working fluid from the furnace wall outlet. Little control of the temperature of this mixed fluid is possible due to the fact that the furnace wall outlet temperature is maintained close to design conditions and the economizer outlet temperature is a function of combustion gas temperature. Since, at start-up and low load, only a small degree of cooling is obtained by the above-noted mixing (due to high economizer temperatures and low percent through-flow), recirculation does not provide a sufficient heat transfer relationship between the circulating mixed fluid and the furnace wall tubes for the adequate protection thereof.

Our invention provides an arrangement for improving furnace wall protection including a bypass for at least a portion of the incoming feedwater around the economizer whereby the temperature of the mixture of the furnace wall outlet fluid and the feedwater from the economizer outlet plus the bypassed feedwater, as delivered to a recirculation pump, is reduced. This fluid temperature reduction permits the amount of fluid mass flow in the furnace wall tubes (and thus the heat transfer characteristics thereof) to be increased. Restated, the reduction in temperature of the fluid mixture delivered to the recirculation pumps reduces the specific volume thereof. The volumetric flow of the pumps is substantially the same under any load condition, so that a lower specific volume results in a higher mass flow to be delivered to the furnace walls. Since higher mass flow creates better heat transfer characteristics, the furnace wall tubes are more able to stand the heat of fuel firing and are thus more adequately protected.

BRIEF DESCRIPTION OF THE DRAWINGS

FIG. 1 is a diagrammatic representation of the flow arrangement of this invention.

FIG. 2 is a graphical representation of the increase in furnace wall mass flow with the increase in economizer bypass line flow.

FIG. 3 is a graphical representation showing the decrease in mixed flow temperature with increase in economizer bypass line flow.

DESCRIPTION OF THE PREFERRED EMBODIMENT

Referring to FIG. 1, during general operation of the once-through steam generator system incorporating our novel arrangement, feedwater is supplied through 10 a conduit 12 to a feedwater supply valve 14. A flow meter 16 provides a signal for an operator 18 which controls the flow through the feedwater supply valve 14. This water is passed serially through an economizer 20 to a mixing vessel 22, and thence through recirculation pump 24 to the furnace wall tubes 26 where it is heated by combustion within the furnace to form steam. The steam leaving the furnace tubes passes through conduit 28 to a superheater 30 from where it is taken through conduit 32 to do useful work such as 20 to operate a turbine (not shown).

A feedwater valve bypass portion 34 having a bypass valve 36 is provided for controlling feedwater flow at very low loads. In parallel with the feedwater supply valve 14 and feedwater valve bypass portion 34 is the 25 economizer bypass portion 38, of our novel arrangement. Economizer bypass portion 38 has an economizer bypass valve 40 which enables a portion of the feedwater to be bypassed around the economizer 20 and flow directly into the mixing vessel 22 at low loads as described hereinbelow. It is pointed out that economizer bypass valve 40 must be parallel to feedwater bypass valve 36 in order to equalize the pressure drop across the economizer 20 and bypass portion 38 to achieve the bypass flow.

At the beginning of start-up of the once-through steam generator system, cold water is recirculated through conduit 42 from the furnace wall tube outlet 44 to the mixing vessel 22 where it is mixed with incoming feedwater when a nominal through-flow of cold water is established. Nominal through-flow (usually about 5 percent of designed full load through-flow) is used to provide improved pressure control and uniform heating of various tubing and headers outside of the recirculating flow path. As the furnace is fired (and load applied), the temperature of the fluid in the furnace wall tubes 26 and in the economizer 20 increases. The temperature of the substantially recirculated flow will then increase to a relatively high temperature (approximately 760° to 800°F). The mixed flow (consisting of fluid from the recirculating conduit and from the economizer) entering the furnace walls 26 from the mixing vessel 22 will then be at a high temperature and a low density, the density varying inversely with the temperature. For example, at 3,500 psi and 200°F, the density is 61.5 lb/ft³ while at 800°F it is 7 lb/ft³.

While the volumetric flow rate during this start-up and low load operation is substantial, the mass flow rate is low due to the low density of the mixed fluid. The metal temperature of the furnace side of the furnace wall tubes is dependent not only on the rate of heat transfer from the furnace gases to the tubes but also the thermal resistance of the tubes and the inside film between each tube and the fluid therein. Since this inside film is a function of mass flow rate rather than velocity or volumetric flow rate, poor heat transfer between the tubes and the fluid is obtained during this period of operation. Therefore, while the furnace is operated at

low loads and relatively low heat adsorption rates (as compared to full load), high local heating rates still may exist in the general area of the burners which can cause damage to the tubes located in this area.

As the amount of through-flow is increased the recirculation is decreased, a greater quantity of incoming feedwater is mixed with a lesser quantity of the relatively hot recirculated water. The mixed water temperature, thus decreases and density increases as the load on the steam generator is increased. Therefore, safe operating conditions for the furnace wall tubes are easily achieved at higher loads where there is substantial through-flow and adequate heat transfer characteristics exist.

A critical condition exists at the low loads up to 30 percent of full load when there exists substantial firing in the furnace and a high quantity of recirculation which leads to high temperatures and low mass flow in the furnace wall tubes. According to our arrangement, in order to increase the mass flow through the furnace wall tubes 26 and thus improve the heat transfer characteristics therein, a portion of the feedwater is bypassed through economizer bypass portion 38 around the economizer 20 and directly into the mixing vessel 22. The temperature of the bypassed feedwater is approximately 220°F as compared to feedwater passed through the economizer which is at a temperature of approximately 500°F. This lower temperature bypassed feedwater reduces the temperature of the mixed fluid which increases its density and mass flow to be delivered to the furnace wall tubes 26.

A temperature sensing device 46 is located between the mixing vessel 22 and the recirculation pump 24 to sense the temperature of the mixed fluid delivered to the recirculation pump 24. The sensed temperature is compared in a controller 48 to a Set Point temperature (desired optimum working fluid temperature) to control an operator 50 according to the difference, or error, signal generated for regulating the amount of feed-water bypassed around the economizer 20 at the above-mentioned loads. As the temperature of the recirculated flow rises, raising the sensed mixed fluid temperature above the Set Point temperature, the amount of fluid bypassing the economizer is increased. This increased temperature — increased bypass association is continued up to about 30 percent load where substantial through-flow will provide sufficient tube wall protection. Therefore, above this point (about 30 percent load) economizer bypass is no longer necessary for tube protection and is discontinued.

Referring to the graph of FIG. 2, it can be seen that the mass flow through the furnace wall tubes can be increased up to a maximum of about 123 percent of normal mass flow by the bypassing of the feedwater around the economizer. As noted in the graph of FIG. 3, the temperature of mixed fluid can be lowered from 718° to 715°F. While a three degree drop in temperature does not appear large, the specific volume change associated therewith is substantial as reflected in the increased mass flow shown in the graph of FIG. 2.

Thus it can be seen that by bypassing a portion of the feedwater around the economizer, the temperature of the mixed fluid circulating in the furnace walls can be reduced. The reduction in temperature results in increase in mass flow which has the effect of promoting better heat transfer characteristics between the tube walls and fluid therein for improved furnace wall pro-

tection during the period of low loads when other protective methods, valid at higher loads, have been found insufficient.

It will be understood that various changes in the details, and arrangements of parts which have been herein described and illustrated in order to explain the nature of the invention, may be made by those skilled in the art within the principle and scope of the invention expressed in the appended claims.

10 What is claimed is:

1. In a once-through steam generator system comprising a furnace with fuel being burned therein establishing the flow of combustion gases therefrom, furnace wall tubes lining the walls of said furnace for radiant heat absorption from the burning fuel within said furnace, heat exchange means in the flow of combustion gases, a first conduit for conveying incoming working fluid into said heat exchange means, a control valve in said first conduit for controlling the flow of incoming working fluid, a second conduit for conveying said working fluid to said furnace wall tubes from within said heat exchange means, a third conduit for conveying the working fluid from said furnace wall tubes after passage therethrough, a fourth conduit providing a recirculation path for the working medium from said third conduit to said second conduit and pump means for recirculating at least a portion of the working fluid through said fourth conduit; an arrangement for protecting said furnace wall tubes comprising:

30   bypass means for selectively bypassing at least a portion of the incoming working fluid around said heat exchange means so that said working fluid enters said furnace walls without being heated in said heat exchange means, said bypass means comprising a fifth conduit connected between said first conduit and said second conduit, a selectively operable valve means in said fifth conduit for regulating the flow therein, said pump means being located in said second conduit downstream of the connection of said fourth and fifth conduits with said second conduit.

35   2. The arrangement of claim 1 wherein said selectively operable valve means is located so as to be in parallel with said control valve.

40   3. The arrangement of claim 1 wherein automatic control means are provided to control said selectively operable valve means of said bypass means, said automatic control means responsive to a condition of the working fluid as it enters said furnace walls.

45   4. The arrangement of claim 3 wherein said automatic control means comprise a temperature sensing means sensing the temperature of the working fluid entering said furnace wall tubes, said means located downstream of the junction of said fourth conduit with said second conduit and said fifth conduit with said second conduit and upstream of said pump means, controller means receiving a signal from said temperature sensing means indicating temperature of the working fluid, said controller means also receiving a Set Point signal indicating the desired working fluid operating temperature, said controller means operative in response to the difference between said received signal to control the regulative position of said selectively operable valve means over at least a portion of the steam generator operating load range.

50   5. A method of operating a once-through steam generator system having a furnace, furnace wall tubes lin-

ing the walls of the furnace for radiant heat absorption, and an economizer, the steps comprising:

establishing a through-flow of incoming working fluid through said economizer and said furnace wall tubes, recirculating a portion of the flow from the outlet of the furnace wall tubes to the entrance of the furnace wall tubes, mixing the recirculated flow and the through-flow upstream of the furnace walls and downstream of the economizer, firing fuel in said furnace thereby increasing the temperature of the mixed working fluid passing through said furnace wall tubes, bypassing at least a portion of the incoming working fluid through-flow around said economizer, regulating said bypassed portion so that the amount of flow bypassed around said econ-

15

omizer is substantial at low loads and discontinued at high loads.

6. The method of claim 5 wherein the step of regulating said bypassed portion comprises the steps: sensing the temperature of the mixed working fluid flow as it enters the furnace wall tubes, comparing the sensed temperature to an optimum desired temperature, controlling the bypassed flow portion during load operation up to 30 percent of full load according to the difference between the sensed temperature and the desired temperature so that the flow around said economizer may be increased, and discontinuing said bypassed flow portion during operating load conditions above 30 percent of full load.
